UNITED STATES PATENT OFFICE.

MAJOR HALL, OF BOISE, IDAHO.

WELL MACHINERY.

1,083,089.

Specification of Letters Patent. Patented Dec. 30, 1913.

Application filed January 30, 1913. Serial No. 745,277.

To all whom it may concern:

Be it known that I, MAJOR HALL, a citizen of the United States, residing at Boise, in the county of Ada and State of Idaho, have 5 invented certain new and useful Improvements in Well Machinery, of which the following is a specification.

My invention relates to improvements in well machinery, and refers particularly to 10 an improved type of cable well-drilling tools, the main object being the provision of a cable-drilling tool which will allow the water and cuttings to pass upward around the tool and upon the lifting of the tool 15 from the ground, permit the liquid or water and cuttings to enter and be discharged through the tool, thus permitting the tool to rapidly effect the drilling operation and at the same time prevent interference by 20 reason of the cuttings.

Another object of my invention is the provision of a cable-operated well-drilling tool which will effect a rapid and perfect boring or drilling and as the cuttings are gathered 25 will cause such cuttings to be carried upward away from the bit to permit the easy and ready operation of the bit free from interference, and also to provide a well-drilling tool which will be of simple, durable, 30 inexpensive and practical construction.

With these objects in view my invention consists of a cable-operating well-drilling tool, embodying novel features of construction, combination and adaptation of parts 35 substantially as disclosed herein.

In order that the construction in detail and the operation of my improvement may be fully understood, and its numerous advantages be appreciated, I have illustrated 40 in the accompanying drawings an embodiment of my invention, it being understood that I reserve the right to make such changes in the construction of my improvement as come within the scope of my invention.

Figure 1 represents a side elevation of a cable-operated well-drilling tool constructed in accordance with and embodying my invention. Fig. 2 represents a vertical sectional view of the well-drilling tool shown 45 on an enlarged scale to more clearly show the detail of construction. Fig. 3 represents an end view of the auger or bit. Fig. 4 is a perspective view of part of the drill. Fig. 5 is a similar view looking at the opposite side of the drill.

Referring by letter to the drawings in

which similar letters of reference are employed to denote corresponding parts in the five views:

The letter A designates the auger or bit 60 which has the corrugated flaring lower portion B, forming the cutting edges C, and has the upper reduced tubular or hollow portion D, provided with the tapered or beveled shoulder E, and the contiguous interiorly 65 threaded stem F.

Any style of cable well-drilling bit may be used with my invention, but I provide a bit with cutting edge of special design so arranged or shaped that it crosses the last 70 place it has cut on the bottom with each revolution of the tool, thus permitting of thinner cutting edge, at the same time by reason of its peculiar shape, obviating the danger of fissuring, or making a flat hole, 75 which is of great importance. As the tool cuts its way into the ground the cuttings are carried upward around the outside of the stem or bar, and are there disintegrated and mixed by the agitation, thus allowing clear- 80 ance on the bottom for the bit to do rapid work free from interference. The bit is also provided with a central vertical channel which is in communication with the central tubular portion of the bit by reason of 85 the tubular passage G, and also opposite side channels, which flare or open outward to form the outer cutting edges as at C, Fig. 5.

To the threaded stem of the bit or auger 90 is connected the lower threaded end H, of the hollow drill bar J, which at its upper end is provided with screw threads L, and the upper and lower edges of the hollow main connection bar are beveled as at M, to 95 make a snug and strong joint. This hollow connecting bar is of any length and by reason of its tubular or hollow construction can be made any diameter desired without adding too greatly to its weight, in order that, 100 in large wells, the space between the stem and the walls of the well may be restricted sufficiently to promote the agitation necessary to disintegrate and mix the cuttings above the bit or auger.

To the upper threaded end of the hollow connecting bar is secured the reduced portion N, of the solid cap O, which is provided with the restricted square upper portion P, for receiving a wrench or implement, and 110 also provided with a series of entrance openings Q, this square portion is formed with

the enlarged cylindrical portion Q', and has the restricted portion R, provided with the exterior threads R', for the purpose of receiving a suitable cable attachment. This 5 solid cap is formed with an opening which is bored upward from the bottom of the cap and intersects a series of openings Q at S. The reduced portion N of the cap is provided with a valve U, which is normally 10 closed and is hinged or otherwise retained at V, being held there by the spring W, which exerts its tension upward and normally retains the valve in closed condition.

In operation the tool being attached to the 15 cable in the usual manner is lowered to the bottom of the well, and being submerged in water is lifted and dropped on the bottom. As the tool is being lifted a vacuum is formed on the bottom, to compensate for 20 which water is drawn downward through the tool and out through the opening in the bit, the valve opening automatically for its passage. When the tool reaches the limit 25 of upward movement the pressure being released on the valve, it closes automatically. The downward movement or drop of the tool forces the water and cuttings up and around the outside of the stem or bar. This 30 operation of the tool being repeated with great rapidity it will be seen a circulation is established down through the tool and upward around the outside of the stem or bar, thus clearing the bottom and affording a 35 new surface for the bit to cut free from interference. When the drilling operation has been continued sufficiently long, or until the tool begins to lag by reason of the sludge around the tool it is run up in the derrick and a sand pump or bailer is lowered and 40 the hole cleaned out. This completes the work or operation of one run.

It will thus be seen that I provide a drilling tool which will effect the boring or drilling in a rapid and perfect manner without

the necessity of having very frequently to 45 remove the tools. Also that the tool will automatically clear the accumulation away from the bit or auger and that generally the improvement will prove economical, efficient and practical from every point of view. 50

I claim:

1. In a well-drilling tool of the class described, consisting of a bit or auger having a tubular upper portion, a cap having an entrance opening and a controlling valve, and a hollow rod connecting the cap and the tubular portion of the bit.

2. A well-drilling tool, consisting of a cap having means for connecting with a cable, and provided with entrance opening and a discharge opening, a hollow connecting rod secured to said cap, a valve carried by said rod and controlling the discharge opening of the cap, and a tubular bit or auger secured to the lower end of said hollow connecting rod.

3. A well-drilling tool, consisting of the cap formed with a stud for connection with the cable, and provided with entrance and discharge opening, a hollow rod having its upper end connected to the discharge end of said cap; a spring-actuated valve for normally closing the discharge opening of the sleeve, a bit or auger having an upper hollow or tubular portion secured to the lower end 75 of the hollow connecting rod and having a flared lower portion provided with cutting edges and with a central channel communicating with the tubular portion thereof and with a pair of side channels leading to the reduced portion of said bit or auger.

In testimony whereof I affix my signature in presence of two witnesses.

MAJOR HALL.
